ABSTRACT: A fluidic transducer having no moving mechanical parts utilizes a two stage fluid amplifier circuit for converting pressurized pneumatic signals to a hydraulic output, or vice versa. A variable fluidic resistance means connected in bridge circuit relationship between the first and second stage amplifiers provides a hydraulic-pneumatic interface therebetween and is comprised of two fluid amplifiers utilizing only the power fluid and control fluid inlets thereof. The outputs of the first stage amplifier are connected to single control fluid inlets of the intermediate fluid amplifiers for controlling the downstream pressure of the power jets therein. The control fluid inlets of the second stage amplifier are connected to the power fluid inlets of the intermediate fluid amplifiers such that a control signal applied to the first stage amplifier causes proportional changes in the downstream pressure of the power jets of the intermediate amplifiers which are reflected into the control fluid inlets of the second stage amplifier.

PNEUMATIC-HYDRAULIC FLUIDIC TRANSDUCER

My invention relates to a pneumatic-hydraulic transducer having no moving mechanical parts, and in particular, to a transducer utilizing analog-type fluid amplifiers in a bridge circuit connection to obtain the desired interface between the pneumatic and hydraulic portions of the device.

Pneumatic-hydraulic transducers are useful in many control systems wherein one of the signals is of the pressurized pneumatic or hydraulic type and a particular circuit in the system utilizes the opposite type fluid signal for processing thereof. Such transducers are especially useful in, but not limited to, systems and circuits employing the recently developed fluid control devices known as fluid amplifiers.

Prior art pneumatic-hydraulic transducers utilize a conventional analog-type fluid amplifier provided with a hydraulic fluid power supply and pneumatic control signals for accomplishing the hydraulic-pneumatic interface. Such prior art approach necessarily results in entrainment of the pneumatic medium in the hydraulic fluid thereby generating a noise due to the mixing process. Other types of prior art pneumatic-hydraulic transducers utilize moving mechanical parts which are subject to wear, fatigue failure, friction and hysteresis. Thus, there is a need for providing a pneumatic-hydraulic transducer having no moving mechanical parts and capable of isolating any noise generated by mixing pneumatic and hydraulic fluids from the output of the transducer.

Therefore, one of the principal objects of my invention is to provide a fluidic-type pneumatic-hydraulic transducer having no moving mechanical parts.

Another object of my invention is to provide such transducer wherein the mixing of the pneumatic and hydraulic fluids and noise generated thereby is isolated from the output of the transducer.

A further object of my invention is to construct the transducer from a bridge circuit arrangement of fluid amplifiers wherein two of the fluid amplifiers function as variable fluidic resistances.

Briefly stated, in meeting the objects of my invention I provide a two stage fluidic amplifier circuit wherein the first stage is an analog-type fluid amplifier provided with a power fluid supply and control fluid signal of a first type fluid which may be pneumatic or hydraulic, and a second stage analog-type fluid amplifier provided with a power fluid supply and control fluid signal of a second type fluid opposite from that in the first stage. Variable fluidic resistance means are connected in bridge circuit relationship between the first and second stage amplifiers for providing a pneumatic-hydraulic interface therebetween. The variable fluidic resistance means comprise two analog-type fluid amplifiers each having a first control fluid inlet connected to an output of the first stage amplifier and the second control fluid inlets being blocked. The power fluid supply for the variable fluidic resistance fluid amplifiers is common with the control fluid supplied to the second stage amplifier whereby changes in the downstream pressure of the power jets in the variable resistance fluid amplifiers are reflected into the control fluid inlets of the second stage amplifier to thereby convert the first type fluid control signal in the first stage amplifier to a control signal of the second type fluid in the second stage amplifier without the use of any moving mechanical parts and providing isolation of any mixing of the two fluids from the control fluid inlets of the second stage.

The features of my invention which I desire to protect herein are pointed out with particularity in the appended claims. The invention itself, however, both as to its organization and method of operation, together with further objects and advantages thereof may best be understood by reference to the following description taken in connection with the accompanying drawings wherein like parts in each of the several FIGS. are identified by the same reference character and wherein:

FIG. 1a is a plan view of a pneumatic-hydraulic transducer constructed in accordance with my invention;

FIG. 1b is a schematic representation of the transducer shown in FIG. 1a;

FIG. 2 is a characteristic curve of the input-output pressures of my transducer when employed as a hydraulic-to-pneumatic transducer; and

FIG. 3 is a family of characteristic curves of the input-output pressures of my transducer when employed as a pneumatic-to-hydraulic transducer.

Referring now in particular to FIGS. 1a and 1b, there are shown conventional fluid amplifiers of the analog (proportional) type designated as a whole by numerals 10 and 11 which comprise the first or input stage and the second or output stage, respectively, of my fluidic transducer. Each of fluid amplifiers 10 and 11 is provided with a power fluid inlet terminating in a fluid flow restrictor or nozzle 12 for generating a power jet of fluid upon the inlet being supplied with a pressurized fluid. A pair of fluid receivers 13 and 14 are disposed downstream of the power fluid nozzle 12 for receiving at least a part of the fluid from the power jet. Intermediate the power nozzle and receivers are a pair of control fluid inlets terminating in opposed fluid flow restrictors or nozzles 15 and 16 for deflecting the power jet in proportion to the magnitude of the differential pressure of the fluid supplied to the control fluid inlets. Intermediate the control nozzles and receivers are disposed a pair of side vent passages 17 and 18 having their outer ends open to the atmosphere or returned to a sump depending upon the particular fluid supplied to the amplifier. A center vent passage 19 is also provided intermediate the receivers.

A first type pressurized fluid which may be pneumatic (any suitable gas including air) or hydraulic (any suitable liquid including oil or water) is supplied to the first stage amplifier 10. Thus, the pressurized power fluid supply P_{s1} and the differentially pressurized input control fluid signal ΔP_{c1} are each of the first type fluid. As a result, the differentially pressurized output of the first stage ΔP_{o1} obtained between receivers 13 and 14 is also of the first type fluid.

The second stage fluid amplifier 11 is provided with a power fluid supply P_{s2} and control fluid signal ΔP_{c2} of a second type fluid which is opposite from that in the first stage amplifier. Thus, if the fluid supplied to the first stage amplifier is pneumatic, the fluid supplied to the second stage is hydraulic, and vice versa.

Variable fluidic resistance means indicated as a whole by numerals 20 and 21 are connected in bridge circuit relationship between the first stage and second stage fluid amplifiers 10 and 11 for providing a hydraulic-pneumatic interface therebetween having no moving mechanical parts. The variable fluidic resistance means 20, 21, comprise what may be described as halves of two identical analog-type fluid amplifiers of the same type as amplifiers 10 and 11. In particular, the variable fluidic resistance means 20 and 21 each comprise a power fluid inlet terminating in a power fluid nozzle 12a and a pair of control fluid inlets terminating in opposed nozzles 15a and 16a. Instead of employing fluid receivers, the remainder of the half amplifiers comprise a cutout portion 22 for venting the power jet to the atmosphere or to a sump.

The output of the first stage amplifier 10 is in fluid communication with single control fluid inlets of the intermediate half amplifiers 20 and 21. Thus, the output of fluid receiver 13 is connected to the control fluid inlet terminating in nozzle 15a of half amplifier 20 by means of a suitable fluid flow passage 23. In like manner, the output of fluid receiver 14 is connected to the control fluid inlet terminating in nozzle 15a of half amplifier 21 by means of fluid flow passage 24. The control fluid inlets terminating in nozzles 16a of half amplifiers 20 and 21 are each blocked such that no control fluid issues from nozzles 16a. Finally, the power fluid inlets of half amplifiers 20 and 21 are connected to power fluid supply P_{s2} through fluid flow restrictors 25 comprising narrow passages providing equal predetermined fluid flow resistance values, and are directly connected to the control fluid inlets of the second stage amplifier by means of fluid flow passages 26 and 27. The power

fluid inlet of the second stage amplifier 11 is also connected to the power fluid supply P_{s_2} but without the intermediate fluid flow restrictors 25 therebetween.

The operation of my fluidic transducer may be described as follows. Assume that the first type fluid supplied to the input stage amplifier 10 is a hydraulic fluid comprising pressurized water. Thus, water at a substantially constant pressure above ambient is supplied from power fluid source P_{s_1} to the power fluid inlet of input amplifier 10 for generating a liquid jet issuing from nozzle 12 in the direction of receivers 13 and 14. The input control fluid signal ΔP_{c_1} supplied to the transducer is a differentially pressurized (water) signal applied to the control fluid inlets of input amplifier 10. A differentially pressurized (water) output ΔP_{o_1} appears across the two receivers 13, 14 of input stage amplifier 10 and is transmitted by means of passages 23 and 24 to the control fluid inlets terminating in nozzles 15a of half amplifiers 20 and 21. Assuming the general case wherein the input control signal ΔP_{c_1} has a differential pressure magnitude other than zero, the pressures of the (water) signal in passages 23 and 24 are unequal. It is further assumed that the second type fluid supplied to the output stage 11 is a pneumatic fluid comprising pressurized air. Thus, air at a substantially constant pressure above ambient is supplied from power fluid source P_{s_2} to the power fluid inlet of output amplifier 11, and such air at a reduced pressure due to resistors 25 is also supplied to the power fluid inlets of the intermediate amplifiers 20 and 21. The unequal hydraulic (water) pressures in passages 23 and 24 result in control fluid (water) jets of unequal pressures issuing from nozzles 15a in the half amplifiers 20 and 21. The unequally pressurized hydraulic control jets in half amplifiers 20 and 21 cause unequal control of the downstream pressure of the pneumatic (air) power fluid jets therein and such unequal power fluid pressures are reflected into the control fluid inlets of the output stage fluid amplifier 11, developing a differentially pressurized pneumatic control signal ΔP_{c_2} thereat. Pneumatic control signal ΔP_{c_2} causes a differentially pressurized pneumatic output ΔP_{o_2} between receivers 13, 14 of output stage amplifier 11 having a magnitude directly proportional to the magnitude of the differentially pressurized hydraulic input control signal ΔP_{c_1} applied to the input stage amplifier 10 and substantially linearly proportional therewith over a particular range of input control signal pressures. The effect produced by the half amplifiers is thus that of a variable fluidic resistance means.

In the special case wherein the input control signal ΔP_{c_1} has a differential pressure magnitude of zero, the pressures in passages 23 and 24 are equal, resulting in equal power fluid pressures reflected into the control fluid inlets of output stage amplifier 11, and a differential pressure magnitude of zero at the output ΔP_{o_2} thereof.

The selection of proper pressure relationships prevents the undesired introduction or mixing of one of the fluid mediums into the portion of the circuit containing the other fluid medium. Thus, the relationship of power fluid supply pressures P_{s_1} and P_{s_2} and the resistance value of fluidic resistors 25 are selected to prevent the mixing of the first fluid medium confined to the circuit defined by first stage amplifier 10 and the control fluid inlets terminating in nozzles 15a of half amplifiers 20 and 21 with the second fluid medium confined to the circuit defined by second stage amplifier 11 and the power fluid inlets terminating in nozzles 12a of half amplifiers 20 and 21. In the case where amplifiers 10 and 11 have identical dimensions, the first stage power fluid supply pressure P_{s_1} is generally of pressure magnitude less than the second stage supply pressure P_{s_2} whether the transducer converts hydraulic-to-pneumatic, or pneumatic-to-hydraulic. Resistors 25 have equal resistance values sufficiently high to prevent control signal attenuation.

Resistors 25 also determine the overall gain of my transducer as defined by the ratio $\frac{\Delta P_{o_2}}{\Delta P_{c_1}}$. The resistance value of resistors 25 is selected to provide a power

fluid supply pressure to half amplifiers 20 and 21 which is in the range of 0 to 0.40 P_{s_2} . The maximum resistance value obviously provides a minimum power fluid pressure to half amplifiers 20 and 21, and resultant maximum gain of the transducer. However, such maximum resistance value decreases the saturation limit of the transducer resulting in a minimum output ΔP_{o_2} . The minimum resistance value results in a maximum output ΔP_{o_2} , minimum gain of the transducer, and noise and stability problems associated with the output stage 11. Thus, the resistance value of resistors 25 is selected to obtain a predetermined sufficiently high gain and saturation limit for the transducer and mixing of the fluid mediums is also prevented in the input and output stages.

FIG. 2 illustrates the input-output characteristics of my transducer when employed, as hereinabove described, as a hydraulic-to-pneumatic transducer wherein the abscissa represents the differentially pressurized hydraulic input control signal ΔP_{c_1} plotted in p.s.i. and the ordinate represents the differentially pressurized pneumatic output ΔP_{o_2} in p.s.i. The particular characteristics illustrated in FIG. 2 were obtained for a hydraulic (water) supply pressure P_{s_1} of 4 p.s.i. and a pneumatic (air) supply pressure P_{s_2} of 5 p.s.i.

FIG. 3 illustrates the input-output characteristics of my transducer when employed as a pneumatic-to-hydraulic transducer of interface circuit for two values (5 and 10 p.s.i.) of hydraulic (water) supply pressure P_{s_2} and a pneumatic (air) supply pressure P_{s_1} of 4 p.s.i. In this figure, the ordinate is also plotted in p.s.i., but the abscissa is in inches of water. It would be expected that, in general, the gain of my transducer when employed as a hydraulic-to-pneumatic transducer is higher than when employed as a pneumatic-to-hydraulic transducer due to the higher density of the hydraulic control fluid impinging on the pneumatic power jet in the half amplifiers.

From the foregoing description, it can be appreciated that my invention makes available a fluidic transducer or interface having no moving mechanical parts and which is adapted for converting pressurized signals of one type fluid medium to a pressurized output of a second type fluid medium wherein the two type mediums are of the pneumatic and hydraulic type. The transducer comprises two stages of analog-type fluid amplifiers and variable fluidic resistance means connected in bridge circuit relationship therebetween. The variable fluidic resistance means comprise the input elements of two fluid amplifiers of the analog-type. Proper selection of the power fluid supply pressures to the four amplifiers prevents a mixing of the two fluid mediums in either the input or output amplifier stages. The avoidance of mixing of the two fluids prevents the generation of noise produced by such mixing and thus provides a high performance transducer compared to conventional pneumatic-hydraulic transducers. My transducer is equally capable of operation as a pneumatic-to-hydraulic transducer and a hydraulic-to-pneumatic transducer.

Having described a preferred embodiment of my fluidic transducer, my invention is defined by the following claims.

I claim:

1. A fluidic transducer for converting pressurized pneumatic signals to pressurized hydraulic signals, or hydraulic to pneumatic, without the use of moving mechanical parts comprising:
  - a first stage analog-type fluid amplifier provided with a power fluid supply and control fluid signal of a first type fluid which may be pneumatic or hydraulic;
  - a second stage analog-type fluid amplifier provided with a power fluid supply and control fluid signal of a second type fluid which may be hydraulic or pneumatic, and being the opposite type fluid from that in said first stage amplifier; and
  - variable fluidic resistance means connected in fluid circuit relationship between said first stage and second stage fluid amplifiers for providing a hydraulic-pneumatic interface therebetween having no moving mechanical parts, the variable fluidic resistance means comprising a pair of analog-type fluid amplifiers disposed intermediate said first and second stage amplifiers, said pair of intermediate

analog-type fluid amplifiers each comprising:
 a power fluid inlet terminating in a nozzle;
 a pair of control fluid inlets terminating in opposed nozzles; and
 a vent downstream of said power nozzle, and aligned therewith.

2. The fluidic transducer set forth in claim 1 wherein a first control fluid inlet of a first of said intermediate fluid amplifiers in fluid communication with a first output of said first stage amplifier, and a first control fluid inlet of a second of said intermediate fluid amplifiers in fluid communication with a second output of said first stage amplifier.

3. The fluidic transducer set forth in claim 2 wherein a second control fluid inlet of each of said pair of intermediate fluid amplifiers being blocked.

4. The fluidic transducer set forth in claim 3 wherein the power fluid inlet of each of said pair of intermediate fluid amplifiers in fluid communication with the power fluid supply of said second stage fluid amplifier.

5. The fluidic transducer set forth in claim 4 wherein a pair of fluidic resistors having equal fluid flow resistances are connected between the power fluid supply to said second stage amplifier and the power fluid inlets of said intermediate fluid amplifiers.

6. The fluidic transducer set forth in claim 5 wherein the control fluid inlets of said second stage amplifier are connected to the junctures of the fluidic resistors and the power fluid inlets of said intermediate fluid amplifiers whereby a differentially pressurized input control signal of the first type fluid applied to the first stage amplifier produces unequal control of the downstream pressure of the power jets in the intermediate amplifiers to thereby reflect such unequal pressures into the control fluid inlets of the second stage amplifier wherein the magnitude of the reflected pressures is proportional to the magnitude of the input control signal.

7. The fluidic transducer set forth in claim 6 wherein said pair of intermediate analog-type fluid amplifiers are of identical construction and dimensions, and selected pressure relationships between the pressures of the power fluid supplied to the power fluid inlets of said first and second stages and intermediate amplifiers prevents undesired mixing of the pneumatic and hydraulic fluids.

8. The fluidic transducer set forth in claim 7 wherein said fluidic resistors have equal resistance values sufficient to provide a power fluid pressure to said intermediate amplifiers which is in the range of 0 to 0.40 of the power fluid pressure supplied to said second stage amplifier.
